(57) **CLAIM**

The ornamental design for a sink, as shown and described.

DESCRIPTION

FIG. 1 is a right, top, front perspective view of a sink embodying our new design;

FIG. 2 is a top plan view thereof;

FIG. 3 is a front elevational view thereof;

FIG. 4 is a right side elevational view thereof, the left side [elevational] elevation view [There of] thereof being a mirror image of the right side shown;

FIG. 5 is a rear elevational view thereof; and,

FIG. 6 is a bottom plan view thereof.

The broken line representations in the figures are for the purpose of illustration only, and form no part of the claimed design.

In a preferred embodiment, the nature of this product is as a plumbing fixture in the form of a sink which is primarily useful for washing various items.

1 Claim, 4 Drawing Sheets

Matter enclosed in heavy brackets [ ] appears in the original patent but forms no part of this reissue; matter printed in italics indicates the additions made by reissue.
